(57) **CLAIM**

The ornamental design for a fender for electric vehicle, as shown and described.

DESCRIPTION

FIG. 1 is a top, front, and left side perspective view of a fender for electric vehicle, showing the new design;

FIG. 2 is a top, rear, and left side perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines illustrate portions of the fender for electric vehicle that form no part of the claimed design.
